US0D1093294S

(12) **United States Design Patent** (10) Patent No.: **US D1,093,294 S**
(45) Date of Patent: ** Sep. 16, 2025

(54) **CHARGER FOR AN ELECTRIC VEHICLE**

(71) Applicants: **Hyundai Motor Company**, Seoul (KR); **Kia Corporation**, Seoul (KR)

(72) Inventors: **Min Kyu Lee**, Hwaseong-si (KR); **Ho Taek Lee**, Hwaseong-si (KR)

(73) Assignees: **Hyundai Motor Company**, Seoul (KR); **Kia Corporation**, Seoul (KR)

(**) Term: **15 Years**

(21) Appl. No.: **35/523,449**

(22) Filed: **Jun. 26, 2024**

(80) **Hague Agreement Data**

Int. Filing Date: **Jun. 26, 2024**

Int. Reg. No.: **DM/238822**

Int. Reg. Date: **Jun. 26, 2024**

Int. Reg. Pub. Date: **Dec. 27, 2024**

(30) **Foreign Application Priority Data**

Mar. 7, 2024 (KR) 30-2024-0009083
